UNITED STATES PATENT OFFICE.

MATTHIAS KOCH, OF CHICAGO, ILLINOIS, ASSIGNOR TO LOUIS SCHULTZ, OF NEW YORK, N. Y.

QUILTING-MACHINE.

SPECIFICATION forming part of Letters Patent No. 447,571, dated March 3, 1891.

Application filed May 25, 1889. Serial No. 312,082. (No model.)

To all whom it may concern:

Be it known that I, MATTHIAS KOCH, of Chicago, in the county of Cook and State of Illinois, have invented a certain new and useful 5 Improvement in Quilting-Machines, of which the following is a specification.

This improvement relates to an improvement 10 in quilting-machines for which I filed an application for United States Letters Patent on the 22d day of September, 1888, said application having been numbered serially 286,110.

In the machine which is the subject of my 15 said prior application there is a series of needles. The needles may be arranged in one or more rows extending in the direction of the length of the needle-bar. Two carriages are employed. The lower carriage travels in a direction transverse to the length of the 20 needle-bar and series of needles. The upper carriage is carried by the lower and is capable of a movement upon the lower in a direction at right angles to the direction of the movement of the lower, and consequently in 25 a direction parallel with the needle-bar and lengthwise of the series of needles. The lower carriage is capable of moving to and fro in the direction mentioned. Its movements are caused by pattern mechanism. The upper 30 carriage is also capable of movement to and fro in the described direction, and its movements are effected by pattern mechanism. As a result of these capabilities of movement in the carriages the fabric to be quilted, which 35 is secured to the upper carriage, is capable of being moved in any and all directions in a plane at right angles to the reciprocation of the needles.

The machine is particularly designed for 40 ornamental quilting, such as the quilting of flowers, leaves, and other fancy irregular patterns. Sometimes these fancy irregular patterns are of such a nature that it is immaterial whether the strip of fabric containing 45 them is turned one way up or the other way up. In such patterns there is usually a repetition of figures, each of which is composed of two similar halves arranged upon two sides of a center line. Other fancy irregular 50 patterns consist of a repetition of figures, each

having two portions or halves on the opposite sides of a center line different in contour or outline.

In patterns of the kind last referred to it makes a very marked difference whether the 55 patterns be held with one end uppermost or in a reverse position. Hence these patterns cannot be used for the right and left edges of a garment and with the corresponding halves or sections of the salient figure of the pattern 60 uppermost on both sides of the garment unless the pattern is reversed, so as to adapt it for the two sides of a garment.

My present improvement has for its object 65 the adapting of the machine of my former application to work in reverse those patterns which have the two halves or portions of the salient figures of different contour. I will describe such portions of a machine embodying my present improvement as will be necessary. 70

In the accompanying drawings, Figure 1 is a plan of such portions of the machine which is the subject of my said former application as are necessary to an understanding of the 75 present improvement, and in this view I have shown additional parts constituting the present improvement. Fig. 2 is a vertical section taken parallel with the needle-bar of the machine. Fig. 3 is a plan of certain parts specially relating to my present improvement. Fig. 4 is a similar view showing these parts, some of them being in a different position and some other parts being added. Fig. 5 is a view of a portion of the back of a machine. Fig. 6 represents a pattern which may be made by this machine organized in one 85 way. This pattern may be called a "right-handed pattern." Fig. 7 represents a pattern which may be made by this machine organized in another way. The latter pattern may be called a "left-handed pattern." 90

Similar letters and numerals of reference 95 designate corresponding parts in all the figures.

A designates the main frame of the machine. B² designates the needle-bar. This has merely a vertically-reciprocating movement. Any suitable mechanism may serve to implement this movement. The shuttle or looping 100

mechanism will be of any suitable character to co-operate with the needles in the usual manner, and hence need not be shown.

The lower of the two carriages D, whereby 5 the fabric to be quilted is supported, is made in two sections or parts. One section travels along a horizontally-extending portion of one of the side pieces of the frame A and the other section similarly travels along a horizontally-extending portion of the other side piece of 10 said frame A. This carriage, it will be understood, travels in a plane forwardly and backwardly of the machine, or, in other words, in a direction at right angles to the length of 15 the needle-bar.

The upper carriage C is supported by rollers d⁷ on the two sections of the lower carriage D. I term this carriage C the "upper" carriage because it serves to support the fabric.

20 The upper carriage has a frame composed of two side pieces c², connected by stretchers or cross-bars c³. The side pieces of the frame have horizontally-extending bar-like portions which travel upon the rollers d⁷. The engagement 25 of these bar-like portions with the rollers d⁷ effects the connection of the two sections of the carriage D, causing said sections to travel in unison. The carriage C travels in a direction at right angles to that in which 30 the carriage D travels, and hence the carriage C travels in a direction parallel with the length of the needle-bar. It is free to travel to and fro in this direction.

The fabric to be quilted is designated by 35 the letter F. It is held by work-holders consisting of pairs of rollers c⁹ c¹⁰, arranged near the opposite ends of the carriage C. Rollers I' I² are shown as fitted to this carriage for holding the fabric before and after quilting.

40 The movements of the lower carriage D to and fro in a direction at right angles to the length of the needle-bar are effected by pattern mechanism comprising rotary pattern wheels or cams. The nature of these being 45 immaterial to the present improvement, I have not illustrated them.

The to-and-fro motions of the upper carriage C in a direction parallel with the length of the needle-bar are effected by pattern 50 mechanism comprising rotary patterns.

I have illustrated this mechanism as far as necessary to enable me to explain my present improvement. This mechanism as far as illustrated I will now describe. The horizontally-extending bar-like portions of the side pieces comprised in the frame of the upper carriage C are provided with toothed racks r, and with these racks engage pinions E, mounted upon a shaft E', which is journaled 55 in one of the sections of the carriage D and caused to move longitudinally to correspond with the motions of the lower carriage, collars e' e² being secured to this shaft outside the side pieces of the referred-to section of 60 the lower carriage to secure this result. The shaft E' extends in one direction considerably 65 beyond the carriage D, and is supported by

a bearing 1, extending from the main frame A. The shaft E' slides within this bearing 1 when it moves with the carriage D. Affixed 70 to the shaft E' is a long pinion E². I mean a pinion long in the direction of its axis. This pinion engages with a rack-bar E³, which is supported from the main frame, and which is capable of a movement at right angles to the 75 length of the shaft E', and consequently in a direction parallel with the length of the needle-bar. The pinion E² is elongated, so that notwithstanding its longitudinal movement corresponding to the movement of the 80 carriage D it will maintain engagement with the rack-bar E³. The rack-bar E³ is reciprocated through a pattern-wheel E⁶, rotated through a main wheel E⁴, deriving motion from a gear-wheel E⁸, mounted upon a shaft 85 E⁷. This shaft E⁷ may be driven with a pawl-and-ratchet movement or otherwise from the main shaft of the machine.

On the main frame A of the machine are fixed two bearings 2 3, for supporting a shaft 90 4. This shaft 4 has affixed to it a pinion 5, for engaging with the long pinion E² aforesaid. The shaft 4 has also affixed to it a pinion 6 in such position that it will engage with the rack-bar E³. When this shaft 4 is fitted 95 in its bearings, the long pinion E² is shifted lengthwise of its shaft nearer the carriage D, so as to prevent its engagement with the rack-bar E³ and cause it to engage with the pinion 5.

100 It will be readily understood that the rack-bar E³ will then impart a rotary motion to the pinion E² in exactly the reverse direction from that in which it will impart motion to the pinion E² during a direct engagement with the latter.

105 It will be readily seen that by my improvement I provide for organizing one machine for producing either a right or a left handed pattern. This is very advantageous in that 110 the machine is adapted to do more than ordinary work with a very slight change, because it enables it to produce patterns for two opposite sides of garments or for any other opposite positions where it is desirable to have a 115 pattern arranged with the same ends or portions uppermost.

What I claim as my invention, and desire to secure by Letters Patent, is—

1. In a quilting-machine, the combination, 120 with a series of needles and two work-carriages arranged one upon the other for supporting and moving the fabric universally in a plane transverse to the reciprocation of the needles and pattern-wheels for moving said 125 carriages, of mechanism, substantially such as described, between one of the carriages and its pattern-wheel, whereby the direction of certain motions of such carriage may be reversed without reversing the pattern-wheel, 130 substantially as specified.

2. In a quilting-machine, the combination, 135 with a series of needles and two work-carriages arranged one upon the other for sup-

porting and moving a fabric universally in a plane transverse to the reciprocation of the needles, of a rack on one carriage, a gear-wheel engaging with the rack, a shaft carrying the gear-wheel, a rack-bar extending over this shaft, a long pinion supported on the shaft so that it may be shifted into or out of engagement with the rack-bar, bearings for a second shaft, and gear-wheels on the second shaft arranged so that when the second shaft is in place and the long pinion is shifted one of these gear-wheels on the second shaft will engage with the long pinion and the other with the said rack-bar, substantially as specified.

15 3. In a quilting-machine, the combination, with a series of needles and two work-carriages arranged one upon the other for supporting and moving a fabric universally in a

plane transverse to the reciprocation of the needles, of a rack r on one carriage, a gear-wheel E , engaging with the rack, a shaft E' , carrying the gear-wheel, a rack-bar E^3 , extending over this shaft, a long pinion E^2 , supported on the shaft so that it may be shifted into or out of engagement with the rack-bar, bearings 2 3 for a second shaft 4 , and gear-wheels 5 6 on the second shaft, arranged so that when the second shaft is in place and the long pinion is shifted one of these gear-wheels on the second shaft will engage with the long pinion and the other with the said rack-bar, substantially as specified.

MATTHIAS KOCH.
